JAMES J. KLEIN, OF NEW YORK, N. Y., ASSIGNEE TO THE SUPERLATIVE NOVELTY CO., OF BROOKLYN, NEW YORK

MATERIAL-DISPENSING DEVICE FOR CONTAINERS

Application filed September 2, 1926. Serial No. 133,273.

This invention relates generally to closure devices for condiment containers and more particularly to a closure means operable to cover or uncover the perforations in a salt 5 or pepper shaker.

It is well known that the unprotected perforated closure members ordinarily employed in connection with salt and pepper shakers are open to the objection that they are un- 10 sanitary in that dust can penetrate through the perforations and thereby gain access to the interior of the containers. In addition, the objectionable effects of moisture, such as is present in the air, on ordinary table salt 15 is well known in that the salt takes up moisture and becomes caked and solidified.

A general object of the present invention is to supply a cover or closure member to be used in connection with perforated caps 20 for condiment holders and, in addition, to provide for the ready uncovering of the perforations in the act of using the container.

With this and other objects in view, the invention comprises a rotatable disk-like 25 member arranged in adjacent relation to the cover cap member of the container and adapted to be rotated to bring the perforations in the disk member into registration with perforations in the cover member through which 30 the contents of the container are distributed as desired.

A feature of the invention resides in an 35 automatic closing effect which is provided for the closure disk, which includes a tension or spring member arranged to automatically rotate the closure disk to closed position. The spring member, which automatically functions to rotate the closure disk to closed position, serves also to form part of 40 an operating means engageable by the fingers of the user to rotate the closure disk to uncovering position with relation to the perforations in the cover cap of the container. The operating member terminates in two op- 45 positely extending actuating members of the push button type. The actuating members extend through the oppositely disposed lateral margins of the end portion of the container or of the closure cap member in po- 50 sitions convenient to have pressure applied

thereto to bring about the opening position of the closure disk.

Other features of the invention will be hereinafter referred to.

Figure 1 is a plan view of a closure mem- 55 ber and actuating means therefor embodying the invention and showing the parts in closing position;

Figure 2 is a view similar to Figure 1 showing the parts in perforation opening or 60 uncovering position;

Figure 3 is a view in vertical section and on an enlarged scale of the parts shown in Figure 1;

Figure 4 is a view in perspective showing 65 a condiment container equipped with the device shown in Figures 1 and 2 and showing the parts in uncovering position;

Figure 5 is a view in side elevation of a 70 condiment container equipped with a dispensing top or closure member embodying a modified form of the invention;

Figure 6 is a view in vertical section of the dispensing top shown in Figure 5 on an 75 enlarged scale;

Figure 7 is a view in horizontal section taken on the lines 7-7 of Figure 6.

Referring to the drawings for a more detailed description of the invention, the upper or closure end of an ordinary form of condiment container is shown at 10 in Figure 1 of the drawings, the closure end being supplied with a number of perforations 11 through which the powdered or otherwise finely divided contents of the container are 80 adapted to be shaken in order to produce the desired seasoning or spicing effect. 85

In order to control the perforations 11 through which the contents of the container are adapted to be fed, a closure disk 12 is pivotally mounted at 13 on the end part 10 of the container. The closure 12 is also provided with perforations as at 14 which may be brought into registration with the perforations 11 in the end member 10 of the container upon rotation of the closure member 12 through a suitable angle. 90

In order to actuate the closure member 12 to open or close the perforations 11 in the 100

container end through which the contents of the container are to be shaken, an operating or actuating member 15 is provided which takes the form of a length or section of wire having a suitable spring tension. The actuating member 15 includes a central section 16 adapted to lie in a diagonal or oblique relation with respect to the longitudinal axis of the actuating member 15. The actuating member terminates in return bends or loop portions 17 at each opposite extremity. The return bends or loop members 17 extend outwardly through slits 18 provided for the purpose in the opposite side walls of the end flange member 19 which is formed on the end of the container. Struck up tongue members 20 are provided in the end wall member 10 of the container in positions at opposite sides of the longitudinal side line 21 which corresponds with the axis of the actuating member 15. The struck up tongue members 20 form guiding or directing members for the free ends 21 of the return loop members 17 of the actuating member 15. By means of this structural arrangement, the loop members 17 may be pressed inwardly toward each other to thereby produce rotation or angular movement of the central section 16 which is attached to the rotatable closure member 12 through its engagement with struck up tongue members 22 formed thereon. Rotation is thereby given to closure member 12 so that the perforations 14 therein are moved into register with the perforations 11 in the end member 10 of the container, as is indicated in Figure 2.

It will be seen that the rotating action of the closure disk members 12 is effected through the connection of the loop or actuating member 17 with opposite ends of the diagonally arranged central section 16 of the member 15. This connection is brought about through bent sections 23 of the wire frame member which comprises the actuating member 15, the bend being adapted to be closed upon itself as indicated in Figure 2 when the loop members 17 are pressed toward each other. It will be seen that upon release of the actuating members 17, the spring tension inherent in the member 15 moves the actuating members 17 to their outward positions and at the same time the return of the bent portions 23 to their normal conformation has the effect of rotating the closure member 12 to its closing position, as indicated in Figure 1 of the drawings.

It will be seen that the construction described is relatively simple and inexpensive and the manner of its application to the commercial and universally used type of container shown can be readily effected without change in the structure of the container itself. The simplicity of structure which is achieved enables the device to be used with

inexpensive containers of the types adapted for production in large quantities.

The closure device and actuating means described are also capable of application to condiment container caps of a different and more expensive construction. In Figures 5, 6 and 7 of the drawings, there is shown a condiment container 24 of a different type and which may be formed of glass or other suitable material. In this case the container cap 25 is removable and is adapted to be placed into closing relation to the container 24 through engagement of screw threads 26 therewith or in any other suitable manner.

In this form of the invention, the supplemental closure means and actuating means therefor are mounted in the closure cap member 25 which is preferably specially constructed for the reception of the supplemental closure disk and its actuating means. The actuating member 27 follows in a general way the conformation of the actuating member 15 described in connection with Figures 1 to 4 of the drawings. A central section 28 has a diagonal or oblique disposition with relation to a closure disk member 29 rotatably seated in a recess 30 formed for the purpose in the interior surface of the end portion 31 of the closure cap member 25. A suitable pin or screw member 32 pivotally or rotatably supports the closure disk 29 within the cap member 31, as indicated in Figure 6. The pivotally extending loop members 33 formed on the actuating member 27 are in this form of the invention enclosed in cap members 34 which not only produces an attractive and finished effect but, by close engagement with the side walls of the orifices 35 in the cap member 25 through which they project, the cap members 34 prevent escape of the contents of the container through the orifices or slots 35. The cap members 34 are clamped into engagement with the loop members 33 by suitably compressing the upper and lower surfaces of the cap as at 36 to force the material of the cap into the loop structure and thereby lock the parts together. It will be seen that in the extended positions of the actuating cap members 34, the perforations 37 in the end wall 31 of the cap member 25 are closed by the position of the closure disk 29. On the other hand, when the actuating members 34 are pressed inwardly toward each other, as between the thumb and finger of the user, the perforations 38 in the supplemental closure disk 29 are moved into registration with the perforations 37 in the cap member to provide the unobstructed perforations through which the contents of the container may be shaken or sifted as desired. It will be seen that in both forms of the invention described a control means for condiment containers has been devised which is readily moved to open position when grasped between the finger and thumb of the user in lifting the

5 container from the table in the most natural position for use. On the other hand, the mere replacing of the container on the table or other surface after use is accompanied by the automatic closing of the perforations in the dispensing top or closure cap thereon.

10 While I have described the container as being adapted particularly for the use of condiments, such as salt and pepper, it will be clear 10 that it may be used equally well for other purposes. For example, it may be used with talcum powder or the like. It will also be clear 15 that while I have shown two actuating members mounted in oppositely extending positions, the rotatable closure member may also 15 be operated by means of a single manually operable actuating member if desired.

20 It will be clear that other adaptations of the invention may be utilized within the scope of 20 the appended claims.

25 What I claim is:

1. In a closure device for condiment containers, a container cap member having perforations therein, a perforated closure member 25 rotatably mounted on the cap member to cover or uncover the perforations in the cap member according to the angular position of the closure member, actuating members for the closure member extending transversely across 30 said cap member and connected to rotate said closure member to perforation uncovering position when moved longitudinally toward each other, and spring means tending to return the parts to perforation covering position 35 when the actuating members are released.

2. In a closure device for condiment containers, a container cap member having perforations therein, a perforated closure member rotatably mounted on the cap member to cover or uncover the perforations in the cap member according to the angular position of the closure member, an operating member for the closure member consisting of a section of spring wire extending across and attached to the closure member, and the terminal portions 40 of the operating member being arranged to extend in opposite directions along an axis inclined to that portion of the wire attached to the closure member and movable longitudinally toward and from each other, whereby movement of the terminal portions toward and from each other will operate the closure member.

3. In a closure device for condiment containers, a container cap member having perforations therein and having a flange projecting endwise from the container, a perforated closure member rotatably mounted on the cap member to cover or uncover the perforations 45 in the cap member according to the position of the closure member, an operating member for the closure member consisting of a section of spring wire extending across and attached to the closure member, and the terminal portions 50 of the operating member being

arranged to extend in opposite directions along an axis inclined to that portion of the wire attached to the closure member, said terminal portions of the wire section projecting through the flange of the cap member for actuation by the fingers of the user, inward pressure on said terminal members operating to rotate the closure member to perforation uncovering position, and the spring tension in said closure operating member operating 70 to rotate the closure member to perforation 75 covering position.

4. In a closure device for condiment containers, a container cap member consisting of a perforated end wall member having a flange 80 projecting endwise from the container in circumscribing relation to said end wall member, a disc shaped closure member rotatably mounted on the outer surface of the perforated wall member, said closure member having 85 perforations therein adapted to be moved into and out of register with the perforations in the wall member, a closure rotating member consisting of a section of wire having a central portion thereof extending across and attached to the outer surface of the rotatable closure member, the wire at the opposite ends of the central portion being bent in opposite directions to form an S, and the terminal portions of the wire section being looped to form oppositely extending actuating members which project through the flange member 90 of the container.

5. In a closure device for condiment containers, a container cap member consisting of a perforated end wall member having a flange 100 projecting endwise from the container in circumscribing relation to said end wall member, a disc shaped closure member rotatably mounted on the outer surface of the perforated wall member, said closure member having 105 perforations therein adapted to be moved into and out of register with the perforations in the wall member, a closure rotating member consisting of a section of wire having a central portion thereof extending across and attached to the outer surface of the rotatable closure member, the wire at the opposite ends of the central portion being bent in opposite directions to form an S, the terminal portions 110 of the wire having return bends therein and extending along an axis inclined to the central portion of the wire, said end wall member 115 being formed to provide guide members engaging the terminal portions for causing 120 the same when actuated to move along said axis, and said terminal members projecting through oppositely disposed portions of said flange for actuation by the fingers of the user.

6. In a closure device for containers, a container cap member having perforations therein, a perforated closure member movably mounted on the cap member to cover or uncover the perforations in the cap member according to the position of the closure mem- 125

ber, and an actuating member for the closure member whose opposite ends extend laterally beyond the side edges of the cap member, the terminal portions of said actuating member being mounted to move simultaneously and alternately toward and from each other to operate the closure member.
